AUGUST G. LIEBMANN, OF BUTTE, MONTANA, ASSIGNOR TO VIGNOLES RAIL CHAIR COMPANY, OF NEW YORK, N. Y., A CORPORATION OF DELAWARE.

RAIL-CHAIR.

1,126,500.

Specification of Letters Patent. Patented Jan. 26, 1915.

Application filed April 28, 1913. Serial No. 764,151.

To all whom it may concern:

Be it known that I, AUGUST G. LIEBMANN, a citizen of the United States, residing at Butte, in the county of Silverbow and State 5 of Montana, have invented certain new and useful Improvements in Rail-Chairs, of which the following is a specification.

This invention relates to track equipment and particularly to means for supporting 10 the rails upon the ties.

The ordinary method of attaching rails to ties by means of spikes is open to many objections. It is expensive to keep the rails properly alined and gaged, the constant jar- 15 ring action of passing trains tends to oscillate the spikes thus enlarging the holes formed by the spikes and loosening the spikes, and further the lateral thrust of the wheel loads tends to shift the spikes later- 20 ally and also tends to tip the rail particularly on curves, thus causing a greater or less withdrawal of the spikes which in course of time will loosen the spikes to a degree ren- 25 dering the track unsafe. Further than this, the changes in level of the rail due to frost or thaw where the rails are spiked upon the ties acts to either withdraw the spikes or if 30 the spikes cannot be withdrawn, acts to shear the base flange of the rail. Further objections to the spike and the reason why 35 the spike contributes to tie destructions are that where a soft wood tie is used the rail and the tie is not held with sufficient firm- 40 ness to prevent impact of the rail. This re- sults in a more or less rapid wearing out of 45 the tie. Further, in driving the spike into any of the softer woods the fibers are broken to an unusual extent. As a result, they do 50 not withstand the lateral pressure of the rail and consequently the spike hole is rapidly 55 increased to such an extent that the spike no longer holds. Water collects in the en- larged hole and decay sets in. Again, when- ever a spike becomes so loose that it no 60 longer holds, it is pulled out and driven in at another point. This constant respiking rapidly ruins the tie, besides adding very 65 greatly to the expense chargeable to the maintenance of way.

The advantage of a construction wherein 70 a screw spike may be used is of course ap- 75 parent. The screw spike, as held by engi- 80 neers, prevents the mechanical injury to the tie at the time when the spike is inserted 85 and when it is once put in, it holds the rail

plate to the tie so firmly that a large part of the wear upon the tie is done away with.

The advantage of chairs or tie plates is also obvious. The tie plate acts to distribute the load from the rail to the tie and prevent the mechanical abrasion of the tie. 60 Where rails are laid directly upon the tie, the narrow base cuts into the tie and by using a broad, flat plate this cutting is very largely eliminated. The greater the size of 65 this plate, of course, the more uniform the distribution of pressure on the tie and the less wear and abrasion.

With these objections in view, the primary object of the invention is the provision of a 70 very simple and effective form of rail chair designed to firmly support the rail under all circumstances and to support the rail against vertical or lateral thrusts and against tipping action.

A further object of the invention is to so form the rail chair that it may be economically made out of an ordinary standard structural element and will also allow for adjustment of gage and shimming of track 80 and rapid disengagement for rail renewals.

A further object of the invention is to so form the chair and the rail engaging brace that the rail may be readily elevated or de- 85 pressed to vertically adjust it or may be laterally shifted within the chair.

A further object of the invention is to provide in connection with a chair of the character described, rail braces which will translate any tipping thrust into practically 90 a lateral thrust.

A further object is to provide means whereby if the level of the rail relative to the tie should be changed, as by the rail being lifted through the action of frost, the 95 rail braces will yield sufficiently to permit this change in level without causing a shearing action upon the base of the rail.

Other objects will appear in the course of 100 the following description.

The invention is illustrated in the accom- 105 panying drawings, wherein:

Figure 1 is a perspective view of a tie and a rail with the improved chair applied thereto; Fig. 2 is a side elevation of the tie and chair, the rail being in section and one of the abutments being in section; Fig. 3 is a plan view partly in section of the construction shown in Fig. 2. Fig. 4 is a per- 110 spective view of one of the drift bolts.

Corresponding and like parts are referred to in the following description and indicated in all the views of the accompanying drawings by the same reference characters.

- 5 Referring to these figures, A designates a tie and B a rail. Disposed between the tie and the rail is a chair comprising a bed plate 2 preferably of a width approximately 10 equal to that of the tie, this chair being formed at opposite ends and along its median plane with vertically disposed abutments 3. These abutments are disposed opposite to each other and are spaced from 15 each other a distance slightly greater than the width of the base of the rail B. The inner face of each abutment is vertical and the outer face is curved downward and outward, the outer edge face of each abutment 20 being shown as coincident with the end of the bed plate though this is not necessarily the case. Each abutment is vertically recessed upon its inner face as at 4. The material forming the inner wall of this recess 25 is extended inward as at 5 to form part of the lower wall or bottom of the recess. This extension 5, however, does not extend out the full depth of the side walls 6 of the recess. Each of these side walls 6 is formed 30 with a plurality of perforations 7, the perforations of one wall, of course, alining with the perforations of the wall opposite. Each of these perforations 7 is provided with a lateral extension 8.
- 35 The bed plate is held upon the tie by screw spikes 9 of the usual and standard construction, these screw spikes having heads which bear upon the upper face of the bed plate, the screw spikes extending 40 through perforations in the bed plate on each side of the abutments and being driven into the tie A. The tie A may be of wood or any other suitable material, as the improved chair is equally adapted to all forms 45 of tie.
- The rail is braced and supported between the abutments by means of rail braces 10. These braces are downwardly and outwardly extended and at their upper ends 50 bear beneath the head of the rail. The lower ends of the braces are enlarged and so formed as to fit over the margin of the base flange of the rail as at 11. The material of the braces is outwardly extended as at 12 55 to form a shank 13 which is inserted in and fits the recess 4 of the corresponding abutment. This shank portion fits the recess 4 snugly enough to prevent any tipping movement of the rail braces parallel to the 60 rail B. The shank 13 of the rail brace is formed with a transverse aperture 14, having a lateral extension 15. The aperture in the extension 13 of each rail brace is adapted 65 to register with the apertures 7 of the side walls 6 of the corresponding abutment.

Passing through these apertures 7 and the aperture 14 is a drift bolt designated 16. This drift bolt is circular in section but one side is formed with a fin 17, the face of this fin being inclined so that transversely the drift bolt is tapered. One end of the drift bolt is formed with a head 18 while the other extremity is screw threaded as at 19 to receive a nut 20. This nut may be of any suitable character, but is shown as being perforated for the introduction of a wrench, pin or spanner. I do not wish to be limited to the means for locking the drift bolt in place, as it is obvious that other means may be provided than the nut 20.

With the parts constructed as before described the rail will be held in its adjusted position against any lateral thrust by means of the rail braces which in turn will be held in their adjusted position by means of the drift bolts 16. Inasmuch as the fins on these drift bolts have wedge-like faces, it will be obvious that by retracting one of the drift bolts and forcing in the other drift bolt, the rail will be shifted transversely of 85 the chair and that it will be held firmly in this shifted position. No special tools are required for this purpose, as it is only necessary to use a spanner or wrench for taking off the nut 20 and a sledge hammer for driving in or driving out one or the other of the wedging or drift bolts, these drift bolts acting as wedges for laterally shifting the rail and braces.

In many cases it is desirable either to 100 temporarily or permanently raise the rail. In this case the drift bolts are removed and then a shim is inserted beneath the base of the rail, lifting the rail and the rail braces upward. These shims will be made of certain standard sizes which will correspond to 105 the distance of the drift bolt openings 7 from each other. After the rail has been raised to the height desired, the drift bolts are again inserted in such manner as to hold 110 the rail from lateral shifting and in the position desired. The nuts 20 are again disposed upon the bolts and lock them in place.

The type of rail chair heretofore described and illustrated is particularly adapted for 115 use in terminal yards where it is necessary to provide a rail chair so constructed as to render impossible the insertion of a foot between the rail and the abutments. In the construction illustrated the inner faces of the 120 abutments are so close to the sides of the rail head that the workman cannot accidentally insert his foot. It is to be particularly noted that the rail chair as described may be easily formed by rolling and pressing. 125 It is also to be noted that any tipping action of the rail is resisted on one side by the opposite downwardly extending rail brace and on the side where the pressure is exerted by the fin on the drift bolt which prevents a 130

rotation of the bolt and prevents therefore a rotation of the brace. If by any chance, as through the action of frost, the rail should be lifted it will be obvious that the drift 5 bolts will be subjected to torsional strain and will yield before the base flange of the rail can shear off. It is to be noted with regard to this chair that primary fastenings, namely, the screw spikes 9 are provided, 10 whereby the chair is held to the tie and secondary fastenings, namely, the drift bolts, whereby the rail is held upon the chair and the rail base held in place. In order to adjust the rails, laterally, it is not necessary to 15 remove the primary fastenings but only necessary to remove the secondary fastenings, adjust the rail and then readjust the secondary fastenings. Inasmuch as the chair is disposed permanently upon the tie, 20 it is economically practical to cover the upper face of the tie with tar or like preservative so as to prevent the action of moisture on the wood of the tie, if the tie is made of wood. Further it is obvious that if it is 25 desired to cant the rail, the tie may be so surfaced or beveled as to give a slight inclination to the bed plate of the chair, or the bed plate may be beveled.

Particular attention may be called in connection with the improved rail chair to the official report of the Block Signal and Train Control Board of the Interstate Commerce Commission, this report being dated June 29, 1912, wherein certain requirements are 30 laid down for rail supports and wherein the board says: "A fundamental defect in design which is most apparent is the failure to realize and appreciate the overturning movement due to the wheel flange pressure 35 against the head of the rail. It is not sufficient that the tie should support the vertical loads and resist directly horizontal thrusts and the tendency of the track to move laterally and longitudinally, but the overturning 40 45 movement must be resisted. In order that the tie may properly support the stresses transmitted to it by the rail, a suitable fastening of the rails to the ties is most essential." Further the report states that 50 "under conditions existing in a large proportion of the railroads in this country the means of adjustment of rail to tie must be such as to admit of blocking up or shimming." The board further says that adequate 55 means should be provided for shimming or for widening gage and this means should not involve lost motion and change of adjustment. It is pointed out that the present rail chair, as heretofore described, 60 conforms to all of the requirements referred to in this report and at the same time that the fastenings are not of a complicated nature and that the chairs may be made relatively cheap.

Having thus described my invention, 65 what is claimed as new is:

1. A rail chair comprising a bed plate having upstanding abutments spaced from each other a distance greater than the width of the base of the rail to be supported, 70 rail braces disposed between the abutments and adapted to engage at their upper ends with the head of the rail and at their lower ends to engage over the base of the rail, the abutments being formed 75 with a vertical series of apertures, and the braces each being formed with an aperture adapted to register with any one of the apertures of the corresponding abutment, and locking means passing through 80 the apertures in the abutments and braces and holding the latter in their adjusted positions.

2. A rail chair comprising a bed plate having upstanding abutments spaced from 85 each other a distance greater than the width of a rail base, rail braces adapted to engage the rail and vertically adjustable with relation to the abutments, and means for securing the rail braces to the abutments 90 in any vertically adjusted position.

3. A rail chair comprising a bed plate having upstanding abutments spaced from each other a distance greater than the width of a rail base, each of said abutments having a vertical series of perforations extending through the perforations, rail braces disposed between the abutments and each engageable at its inner end with a rail and being vertically adjustable therewith, each brace being formed with an extension overlapping the abutment and formed with a transverse perforation adapted to align with any of the perforations of the corresponding abutment, and means extending through the perforation 100 for laterally adjusting the said braces relative to the abutment.

4. A rail chair comprising a bed plate having upstanding abutments spaced from 110 each other a distance greater than the width of a rail base, each of said abutments having a vertical series of perforations extending parallel to the rail to be supported, rail braces disposed between the 115 abutments and each engageable at its inner end with a rail and being vertically adjustable therewith, each brace being formed with an extension overlapping the abutment and formed with a transverse perforation 120 adapted to align with any of the perforations of the corresponding abutments, and wedging members passing through said perforations in the abutments and braces.

5. A rail chair comprising a bed plate having upstanding abutments spaced from each other a distance greater than the

- width of a rail base, each of the said abutments having a vertical series of perforations, rail braces disposed between the abutments and each engageable at its inner 5 end with a rail and being vertically adjustable therewith, each brace being formed with an extension overlapping the abutment and formed with a transverse perforation adapted to aline with any of the 10 perforations of the corresponding abutment, and wedging members passing through said perforations in the abutments and braces, each wedging member having a longitudinally inclined vertical 15 face.
6. A rail chair comprising a bed plate having upstanding abutments spaced from each other a distance greater than the width of a rail base, each of said abutments having a vertical series of perforations, rail braces disposed between the abutments and each engageable at its inner 20 end with a rail and being vertically adjustable therewith, each brace being formed with an extension overlapping the abutment and formed with a transverse perforation adapted to aline with any of the 25 perforations of the corresponding abutment, and wedging members passing through said perforations in the abutments and braces, each wedging member having a longitudinally inclined vertical 30 face, and each wedging member having a fin extending longitudinally the whole length 35 of the member on one side thereof, the face of this fin being inclined to the longitudinal axis of the wedging member.
7. A rail chair comprising a bed plate having upstanding abutments spaced from each other a distance greater than the width of a rail base, each of said abutments having a vertical recess on its inside face, rail braces disposed between said abutments and adapted to engage a rail supported on the chair, each brace having an 40 extension projecting into the recess of the corresponding abutment, and wedging members passing through the lateral walls of each abutment and through the extension of 45 the corresponding brace.
8. A rail chair of the character described 50 including a bed plate having upstanding abutments formed integral therewith and disposed opposite to each other, the abutments being spaced from each other a distance greater than the width of a rail base, each of said abutments on its inside face being vertically recessed, the lateral walls of 55 the recess being formed with perforations, each of said perforations being formed with a lateral extension, rail braces disposed between 60 said abutments, each brace comprising a downwardly and outwardly disposed portion and a horizontal outward extension, the 65 extension of each brace being formed with

a transverse perforation having the same form as the perforations in the walls of the corresponding recess, drift bolts, one for each abutment, passing through the perforations in the side walls of the recess and 70 through the perforation in the extension of the rail brace, each one of said bolts being provided with a lateral fin, the face of the fin being inclined from one end to the other toward the axis of the bolt, and means carried on the bolt for holding it in adjusted 75 position.

9. A rail chair of the character described including a bed plate having upstanding abutments spaced from each other to permit the disposal of a rail between them, rail engaging members disposed between the abutments, and means engaging the rail engaging members with the abutments at 80 different levels.

10. A rail chair of the character described including a bed plate having upstanding abutments spaced from each other to permit the disposal of a rail between them, rail engaging members disposed between the abutments, and means carried by the abutments for wedging said rail engaging members laterally and holding them in any 85 vertically adjusted position.

11. A rail chair of the character described including a bed plate having upstanding abutments spaced from each other to permit the disposal of a rail between them, rail engaging members disposed between the abutments, and wedging members 90 extending through said abutments and engaging the rail engaging members and acting to wedge the rail engaging members laterally and to hold them in any vertically 95 adjusted position.

12. In a rail chair, a bed plate having an upstanding abutment, and a rail engaging member coacting with the abutment and adjustable laterally and vertically with respect to the bed-plate, said rail engaging member and the abutment having registering perforations and a bolt engaging the said member to the abutment and passing through said perforations, said bolt having a wedging face.

13. In a rail chair, a bed plate having an upstanding abutment, a rail engaging member coacting with the abutment, said rail engaging member and the abutment having registering perforations and a bolt holding 110 said member to the abutment and passing through said perforations, said bolt having a tapered fin extending longitudinally along the bolt.

14. In a rail chair, a bed plate having an 125 upstanding abutment, a rail engaging member coacting with the abutment, said rail engaging member and the abutment having registering perforations and a bolt holding said member to the abutment and passing 130

through said perforations, said bolt having a tapered fin extending longitudinally along it, and the perforations in the abutment and rail engaging member being formed with 5 lateral enlargements in which the fin is accommodated.

15. In a rail chair, a bed plate having abutments, a rail brace adjustable laterally and vertically with respect to the bed-plate, 10 and means passing through the abutments and brace, and adapted to wedge the brace laterally with relation to the abutments.

16. In a rail chair, a bed plate having an abutment, a rail brace adjustable laterally 15 and vertically with respect to the bed-plate, and means locking the brace to the abutment, and adapted to exert a lateral wedging action upon the brace.

17. In a rail chair, a bed plate having an 20 abutment, a rail brace adjustable laterally and vertically with respect to the bed-plate, and means locking the brace to the abutment, said means being adapted to exert a wedging action laterally and vertically 25 upon the brace.

18. The combination with a bed-plate having oppositely disposed abutments, of a rail adapted to rest on the bed-plate or on

a shim between said abutments and adjustable laterally and vertically with respect to 30 the bed-plate, braces disposed on opposite sides of the rail and engaging said rail and abutments, and means coöperating with the braces and abutments whereby the rail may be adjusted laterally and held in vertically 35 adjusted positions.

19. A rail chair of the character described comprising a base plate having oppositely disposed pairs of upstanding abutments spaced from each other a distance 40 greater than the base flange of a rail, the abutments of each pair being provided with perforations, oppositely disposed rail braces disposed inward of the abutments and adapted to engage a rail between them, each 45 of said rail braces having a lateral perforated extension engaging between the adjacent pair of abutments, and fastening devices passing through the perforations of the abutments and the rail brace extensions. 50

In testimony whereof I affix my signature in presence of two witnesses.
